(57) **CLAIM**

The ornamental design for personal computer dashboard, as shown and described.

DESCRIPTION

FIG. 1 is a front elevational view of a personal computer dashboard showing our new design;

FIG. 2 is a top plan view thereof;

FIG. 3 is a left-side elevational view thereof;

FIG. 4 is a right-side elevational view thereof; and,

FIG. 5 is a view taken along line 5—5 of FIG. 4 showing only the personal computer dashboard on an enlarged scale. The broken line showing portions of a computer housing in FIGS. 1-4, the broken line showing of icons in the central oval of the personal computer dashboard in FIGS. 1, 2 and 5, and the dotted horizontal line and the textual display portion in the central oval of the personal computer dashboard in FIGS. 1, 2 and 5 are for illustrative purposes only and form no part of the claimed design.
